CLAIM

The ornamental design for a glove with pockets, as shown and described.

DESCRIPTION

FIG. 1 is a top perspective view of the first embodiment of a left-hand glove with pockets, according to the claimed design

FIG. 2 is a front elevation view thereof;

FIG. 3 is a back elevation view thereof;

FIG. 4 is a left side elevation view thereof;

FIG. 5 is a right side elevation view thereof;

FIG. 6 is a top plan view thereof;

FIG. 7 is a bottom plan view thereof; and

FIG. 8 is a front perspective view thereof, worn on a left-hand of a person.

FIG. 9 is a top perspective view of the first embodiment of a right-hand glove with pockets, according to the claimed design;

FIG. 10 is a front elevation view thereof;

FIG. 11 is a back elevation view thereof;

FIG. 12 is a left side elevation view thereof;

FIG. 13 is a right side elevation view thereof;

FIG. 14 is a top plan view thereof;

FIG. 15 is a bottom plan view thereof; and

FIG. 16 is a top perspective view thereof, worn on a right hand of a person.

FIG. 17 is a top perspective view of the second embodiment of a left-hand glove with pockets, according to the claimed design;

FIG. 18 is a front elevation view thereof;

FIG. 19 is a back elevation view thereof;

FIG. 20 is a left side elevation view thereof;

FIG. 21 is a right side elevation view thereof;

FIG. 22 is a top plan view thereof;

FIG. 23 is a bottom plan view thereof; and

FIG. 24 is a front perspective view thereof, worn on a left-hand of a person.

FIG. 25 is a top perspective view of the second embodiment of a right-hand glove with pockets, according to the claimed design;

FIG. 26 is a front elevation view thereof;

FIG. 27 is a back elevation view thereof;

FIG. 28 is a left side elevation view thereof;

FIG. 29 is a right side elevation view thereof;

FIG. 30 is a top plan view thereof;

(Continued)

FIG. 31 is a bottom plan view thereof; and
 FIG. 32 is a top perspective view thereof, worn on a right hand of a person.
 FIG. 33 is a top perspective view of the third embodiment of a left-hand glove with pockets, according to the claimed design;
 FIG. 34 is a front elevation view thereof;
 FIG. 35 is a back elevation view thereof;
 FIG. 36 is a left side elevation view thereof;
 FIG. 37 is a right side elevation view thereof;
 FIG. 38 is a top plan view thereof;
 FIG. 39 is a bottom plan view thereof; and
 FIG. 40 is a front perspective view thereof, worn on a left-hand of a person.
 FIG. 41 is a top perspective view of the third embodiment of a right-hand glove with pockets, according to the claimed design;
 FIG. 42 is a front elevation view thereof;
 FIG. 43 is a back elevation view thereof;
 FIG. 44 is a left side elevation view thereof;
 FIG. 45 is a right side elevation view thereof;
 FIG. 46 is a top plan view thereof;
 FIG. 47 is a bottom plan view thereof; and
 FIG. 48 is a top perspective view thereof, worn on a right hand of a person.
 FIG. 49 is a top perspective view of the fourth embodiment of a left-hand glove with pockets, according to the claimed design;
 FIG. 50 is a front elevation view thereof;
 FIG. 51 is a back elevation view thereof;
 FIG. 52 is a left side elevation view thereof;
 FIG. 53 is a right side elevation view thereof;
 FIG. 54 is a top plan view thereof;
 FIG. 55 is a bottom plan view thereof; and
 FIG. 56 is a front perspective view thereof, worn on a left-hand of a person.
 FIG. 57 is a top perspective view of the fourth embodiment of a right-hand glove with pockets, according to the claimed design;
 FIG. 58 is a front elevation view thereof;
 FIG. 59 is a back elevation view thereof;
 FIG. 60 is a left side elevation view thereof;
 FIG. 61 is a right side elevation view thereof;
 FIG. 62 is a top plan view thereof;
 FIG. 63 is a bottom plan view thereof; and
 FIG. 64 is a top perspective view thereof, worn on a right hand of a person.
 The dash-dash broken lines in the drawings represent stitching and form no part of the claimed design. The dot-dot-dash broken lines in the drawings represent environment and form no part of the claimed design.
 The dot-dash broken lines in the drawings represent portions of the glove with pockets and form no part of the claimed design.
